US00D897084S

(12) **United States Design Patent** (10) **Patent No.:** **US D897,084 S**
Andrews (45) **Date of Patent:** **** Sep. 29, 2020**

(54) **SHOE BUMPER**

(71) Applicant: **WORLDOLUXE LLC**, Chicago, IL (US)

(72) Inventor: **Elizabeth M. Andrews**, Chicago, IL (US)

(73) Assignee: **WORLDOLUXE LLC**, Chicago, IL (US)

(**) Term: **15 Years**

(21) Appl. No.: **29/645,042**

(22) Filed: **Apr. 23, 2018**

Related U.S. Application Data

(63) Continuation-in-part of application No. 29/601,218, filed on Apr. 20, 2017, now Pat. No. Des. 825,908, and a continuation-in-part of application No. 15/219,831, filed on Jul. 26, 2016, now abandoned, and a continuation-in-part of application No. 15/091,747, filed on Apr. 6, 2016, now Pat. No. 10,638,814, and a continuation-in-part of application No. 29/551,561, filed on Jan. 14, 2016, now Pat. No. Des. 851,874, and a continuation-in-part of application No. 14/938,443, filed on Nov. 11, 2015, now abandoned.

(57) **CLAIM**

The ornamental design for a shoe bumper, as shown and described.

DESCRIPTION

FIG. 1 is a front, top, perspective view of a shoe bumper showing my new design.

FIG. 2 is a front elevation view of FIG. 1.

FIG. 3 is a rear elevation view of FIG. 1.

FIG. 4 is a left side elevation view of FIG. 1.

FIG. 5 is a right side elevation view of FIG. 1.

FIG. 6 is a top elevation view of FIG. 1; and,

FIG. 7 is a bottom elevation view of FIG. 1.

The dash-dash lines illustrate portions of the shoe bumper which form no part of the claimed design.

1 Claim, 5 Drawing Sheets
